UNITED STATES PATENT OFFICE

2,662,331

FISHHOOK DISLODGING AND EXTRACTING
INSTRUMENTBenjamin F. Borup, Huntington Park, Calif., as-
signor of one-half to Bob F. Borup, Huntington
Park, Calif.

Application January 29, 1951, Serial No. 208,346

1 Claim. (Cl. 43—53.5)

1

This invention relates to certain new and desirably useful improvements in instruments which are expressly adapted to aid a fisherman in aptly meeting and coping with the often tedious and exasperating task of dislodging and extracting a fish-hook, which has become caught, from the mouth of a fish.

An object of the invention is to structurally, functionally and otherwise improve upon prior art extractors through the adoption and use of a simple, efficient and suitably constructed instrument which is properly intended to serve, in an adept manner, the everyday needs of the user.

Another object of the invention is realized through the adoption of an instrument which, because it is fashioned from a single length of wire rod, meets the practical requirements of manufacturers.

In keeping with the prerequisite of greatest possible simplicity, it is a further object to provide a construction which, as a result of experimentation and frequent testing, reveals that no special instructions for use are required, this due to the fact that the mode of handling the collective features is self-evident.

Structurally, a significant aspect of the instrument has to do with a rigid shank having handle means at one end, a corkscrew-like self-feeding fish-hook disgorger at the other end, and novelly convenient means intermediate its ends, whereby the usual leader may be wrapped thereon, effectively snubbed and held with the same hand which operates the instrument, whereby to readily dislodge and then yank the fish-hook free from the mouth of the fish.

In particular, novelty is predicated on the above construction wherein said means is a simple U-bend situated midway between the handle means and disgorger, said bend projecting at right angles from said shank.

Other objects, features and advantages of the invention will become more readily apparent from the following detailed description taken in conjunction with the views of the drawing.

In the accompanying sheet of drawings, where-in like numerals are employed to designate like parts throughout the views:

Figure 1 is a side elevational view of a fish-hook dislodging and extracting instrument constructed in accordance with the principles of the invention and showing the manner in which same is to be used; and

Figure 2 is a perspective view of the instrument per se.

Referring now to the views of the drawings and

employing reference numerals and accompanying lead lines, it will be seen that the complete instrument is made from a single length of wire rod of appropriate gage and rigidity. The main reach of the rod constitutes a shank and this is denoted by the numeral 4. At its outer end the shank is formed into a ring or the like 6 and this constitutes an appropriate handle of hand grip. The opposite end of the rod is formed into a corkscrew-like disgorger which is generally denoted by the numeral 8. The latter is formed from one and one-half helical coils, the main coil being denoted at 10 and the half-coil at 12. The free end of the half-coil is convolved to provide a guiding, retaining and endthrust tip 14. It is obvious that this means 8 is adapted to be "screwed" on the usual leader 16, slid along the shank of the hook and lodged in the seat 18 of the hook, in the manner shown in Figure 1.

20 The intermediate portion of the rod is formed into a lateral substantially U-shaped bend 20 having a bight portion 22 and limbs 24 and 26 which converge toward the bends 28. This U-shaped member provides a leader snubbing member and the leader is adapted to be wrapped around the restricted or neck portion as denoted at 30. The adjacent end portion of the leader 32 is adapted to be run alongside of the shank and held with the same hand which is employed to grasp the finger-ring or hand grip 6, this in an obvious manner.

25 In practice, the disgorger 8 is threaded and screwed on the leader and slid down the shank of the hook until the coils 10 and 12 are lodged in the seat of the hook. This brings the tip 14 into endthrust engagement with said seat. By wrapping the leader 16, as at 30, around the snubbing member 20 and holding the end portion 32 with the hand which also holds the finger-ring, the device is ready to be used. All that is necessary is to hold the fish in one hand and the instrument thus arranged with the other hand, whereupon a suitable thrust action will dislodge the fish-hook, after which it may be extracted 40 from the mouth of the fish 34 in an obvious manner.

45 From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifica-

tions and equivalents may be resorted to, falling within the scope of the appended claim.

Having described the invention, what is claimed as new is:

A fish hook dislodging and extracting instrument comprising a rigid rod member having a rigid shank, the latter being essentially straight and having helically coiled terminal means at its outer end adapted to be "screwed" on a flexible leader and manually forced into end thrust engagement with a fish hook, said shank having a finger-ring on its inner end, the intermediate portion of said shank having a substantially U-shaped leader wrapping and snubbing member, the latter embodying opposed coplanar limbs connected at corresponding ends by way of a

curvate bight portion and connected at opposite ends to the respective complementary shank portions by way of right angled bends.
